United States Patent Office

Des. 218,018
Patented July 14, 1970

218,018

BOTTLE

Marcel Lattraye, Vittel, Vosges, France

Filed Apr. 23, 1969, Ser. No. 16,875

Term of patent 14 years

Int. Cl. D9—01

U.S. Cl. D9—61

FIG. 1

FIG. 1 is an elevational view of a bottle showing my design;

FIG. 2 is an elevational view looking from the left of FIG. 1;

FIG. 3 is an elevational view showing the side opposite that seen in FIG. 2;

FIG. 4 is a sectional view taken on the line 4-4 of FIG. 2; and

FIG. 5 is a sectional view taken on the line 5-5 of FIG. 3.

I claim:

The ornamental design for a bottle, as shown.
